US00D992118S

(12) **United States Design Patent** (10) **Patent No.:** **US D992,118 S**
(45) **Date of Patent:** **** Jul. 11, 2023**

(54) **ATTACHMENT FOR DENTAL APPLIANCE**

(71) Applicant: **SHANGHAI SMARTEE DENTI-TECHNOLOGY CO., LTD.**,
Shanghai (CN)

(72) Inventors: **Tao Guo**, Shanghai (CN); **Jingting Lu**,
Shanghai (CN); **Ziqing Xu**, Shanghai (CN);
Te Wang, Shanghai (CN);
Jianyu Jiang, Shanghai (CN); **Gang Shen**,
Shanghai (CN); **Xingxing Wang**,
Shanghai (CN); **Gang Wu**, Shanghai (CN);
Junfeng Yao, Shanghai (CN)

(73) Assignee: **SHANGHAI SMARTEE DENTI-TECHNOLOGY CO., LTD.**,
Shanghai (CN)

(**) Term: **15 Years**

(21) Appl. No.: **29/808,915**

(22) Filed: **Sep. 23, 2021**

(30) **Foreign Application Priority Data**

Mar. 26, 2021 (CN) 202130165807.1

Primary Examiner — Wan Laymon

(57) **CLAIM**

The ornamental design for an attachment for dental appli-
ance, as shown and described.

DESCRIPTION

FIG. 1 is a perspective view of an attachment for dental
appliance showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the
attachment for dental appliance that form no part of the
claimed design.

1 Claim, 8 Drawing Sheets
